UNITED STATES PATENT OFFICE.

FRANCIS R. HARDIE, OF SALT LAKE CITY, UTAH.

ATTACHMENT FOR CONCENTRATORS.

1,249,078.

Specification of Letters Patent.

Patented Dec. 4, 1917.

Application filed October 30, 1916. Serial No. 128,521.

To all whom it may concern:

Be it known that I, FRANCIS R. HARDIE, a citizen of the United States, residing at Salt Lake City, Salt Lake county, State of Utah, have invented a new and useful Attachment for Concentrators, which consists of certain new and useful attachments which may be fastened on and operated by concentrators now in use with little or no changes or may be constructed on and operated in conjunction with new concentrators to increase the extraction and reduce the cost of operation.

I attain these objects by attaching to concentrating vanners the mechanism illustrated in the accompanying drawings.

Figure 1 represents a view of the invention disconnected from the concentrating vanner to which it is to be attached, parts cut away.

Fig. 2 represents the invention in its general position as it is attached to any concentrating vanner, but the iron spool, 36, in this drawing, is shown as it is attached to the main driving shaft, 51 (immediately in front of the front eccentric, 52), on vanners of the "Johnston" type.

Fig. 3 is a longitudinal section of one of the adjusting elements.

Fig. 4 is a view in perspective of another one of the adjusting elements, parts cut away.

Fig. 5 is a detail in perspective of one end portion of the padded roller, parts cut away.

Fig. 6 is a view in perspective of one of the hinged bearings and coil springs, 33.

Fig. 7 is a longitudinal section of the oil cup and the worm, pinion, shaft and adjusting elements, the worm being shown partly in elevation.

Fig. 8 is a vertical section showing a portion of the vanner belt, brush, padded roller and rod, spray pipes and connected parts.

The vanner belts now in use whether having a plain, a corrugated or an indented surface frequently become coated with a hard scaly matter or with a slimy substance to such an extent that metallic values are lost, and the present invention is intended to prevent such formations, and also to thoroughly and economically clean the belt of all values and save them, after the metal particles are deposited thereon. The cleaning is effected by the co-acting brush, roller and sprays, constructed and operated in the manner hereinafter explained. The saving

of the values is effected by the individual and collective adjustments and the position of the brush, roller and sprays in connection with a trough and other elements as hereafter described.

For purposes of identification, the various parts of this invention, and the parts of the concentrating vanners to which it is to be attached are numbered and described as follows:

The present invention is placed horizontally over the water box 47, immediately in front of the lower part of the vanner as shown in Fig. 2, and consists of: a cylindrical brush 1, which is placed against and contacts with the vanner belt 48, as shown in Fig. 2. Into the ends of the brush the stub shafts 19 are fastened, and these extend outward and are mounted in the bearings 20 in the slots in the standards 16, as shown in Fig. 1.

A rod 2 is placed lengthwise of the brush 1, and near enough that the bristles strike the rod as the brush is rotated. The ends of the rod extend outward and through slots in the standards 16 as shown in Fig. 1.

A perforated pipe 3 is placed lengthwise of the brush 1 near the top and back of it in order that water from this pipe will spray the vanner belt 48, and wash the brush. The ends of this pipe extend outward and through slots in the standards 16 as shown in Fig. 1.

A padded roller 4 is placed lengthwise of the brush 1, below and slightly back of the brush, and so arranged as to contact with the vanner belt 48, and low enough in the water box 47 that its lower part passes through the water in the box, and is so arranged that its padded face contacts with the inside padded edge 6 of the discharging trough 7. In the ends of the padded roller 4, the stub shafts 12 are fastened and extend outward and are mounted in bearings similar to the bearings 20, in slots in the standards 16 as shown in Fig. 1.

A perforated pipe 5 is placed lengthwise of the padded roller 4, in front and low enough to spray the padded roller and the inside padded edge 6 of the trough 7 at the point of their contact. The ends of this pipe extend outward and through slots in the standards 16 as shown in Fig. 1.

Water is supplied to the pipes 3 and 5 through the main pipe 50, and the hose 38.

A discharging trough 7 is placed length-

wise of the padded roller 4, immediately below the roller and with the inside edge 6, of the trough 7 extending as close to and as far under the padded roller as is possible 5 and still keep the bottom of the trough above the water in the box 47.

One end of the trough 7 is slightly lower than the other end so the concentrates will readily discharge out of the spout 8, through 10 the funnel 9, and into the launder 49. The trough 7 is fastened to the braces 57 of the vanner by the braces 10, and being fastened to the vanner it receives the cross motion of the vanner, which motion discharges the 15 concentrates from the trough.

The device is mounted on the bases 15 which have longitudinally disposed grooves in their upper faces, into which grooves the standards 16 are placed, as shown in Fig. 1. 20 These standards are adjusted in the grooves by the screws 17.

The brush 1, the padded roller 4, the pipes 3 and 5, and the rod 2 are mounted in slots in the standards 16, and are adjusted in 25 relation to each other and to the vanner belt 48 by the adjusting screws 21.

The bases 15 are vertically adjusted by the screw legs 22.

To accommodate these adjusting devices 30 cuts are made in the ends of the water box 47, over which cuts are placed the water shields 11 to prevent water slopping out.

Power to operate the brush 1 and padded roller 4 is secured by attaching the spool 36 to a power shaft of the vanner. The belt 34 is placed around this spool, and passes around the pulley 35, which pulley fastens to and rotates the shaft 32, which shaft is mounted in the hinged bearings 31. The 40 coil springs 33 take up any slack in the belt 34 and automatically adjust any variation in the mechanism.

The worm 27 is secured on the shaft 32, and is rotated thereby. This worm 27 engages 45 with the wheel 23 which is fastened on the shaft 12 of the padded roller and rotates it in the opposite direction from that in which the vanner belt 48 is moving at its point of contact with the padded roller.

50 The adjustable driving rod 25 connects the wheels 23 and 24, and imparts the motion of the wheel 23 to the wheel 24, and this wheel is fastened on the shaft 19 of the brush 1, and said brush is thereby rotated 55 in the opposite direction from that in which the vanner belt 48 is moving at its point of contact with the brush.

The adjusting screw 28 regulates the position of the worm 27 to the wheel 23, and the 60 worm is turned in the oil cup 29.

The operation of my invention is as follows:

When the vanner is in operation power is applied through the spool 36 around which 65 the belt 34 is placed, and this belt passes

around the pulley 35 which is fastened on the shaft 32. As this shaft rotates the worm 27 imparts motion through the wheel 23 to the shaft 12 of the padded roller 4, and the roller is made to rotate in the opposite direction to the travel of the vanner belt 48 where the two contact. 70

Through the drive rod 25 propelling the wheel 24 the brush is also made to rotate in the opposite direction to the travel of the 75 said belt 48 where the two contact.

The water flowing through the pipe 3 will fall as a spray on the vanner belt 48 and cylindrical brush 1 at their point of contact and the mineral particles will be caught by 80 the bristles of the brush and will be carried forward and away from the said belt and as the bristles of the brush are brought in contact with the rod 2, the mineral particles will be rubbed and washed from the 85 brush and fall into the trough 7.

Any matter that may remain on the belt 48 after it passes the brush 1 will be scraped from the face of the belt by the padded roller 4 as it rotates in the opposite direction to the travel of the said belt, and be carried by the roller and be scraped from the face thereof by the curved up padded edge 6 of the trough 7, and the mineral particles will be discharged by said trough 95 through the spout 8 and funnel 9 into the launder 49.

To make the said mineral particles leave the face of the said roller more easily, water is supplied through the pipe 5 in the form 100 of spray on the points of contact between the roller face and the padded edge 6 of the trough 7. The face of the roller 4 is also subjected to washing in the water box 47 by touching the water therein. 105

The said vanner belt 48 is given a lateral or cross motion as well as the longitudinal travel, which movements aid in the action of my attachments in cleaning the said belt of concentrates and in keeping the belt in 110 condition to effect complete concentration.

The discharge trough 7 being fastened to the braces 57 of the vanner receives the lateral motion of the vanner which forces the concentrates out of the trough, through the 115 funnel 9, and into the launder 49, and scrapes from the padded roller any mineral particles adhering thereto and deposits them in the trough.

By these operations the vanner belt is 120 kept clean and in a condition to handle its greatest tonnage; to effect the greatest saving of values; the labor of handling the concentrates is saved; and the use of water is reduced to a minimum. 125

Having thus described my invention I desire to secure by Letters Patent and claim:-

1. An attachment of the class described consisting of a vanner belt, a horizontally disposed brush; a padded roller below and 130

- parallel with said brush; means to spray the said brush and roller; a longitudinally movable inclined trough below said roller; one edge of which is bent to contact with the 5 surface of said roller; means to adjust the said brush and roller; and means to operate said brush, roller and trough from the vanner with which the attachment is used.
2. An attachment for concentrator of the 10 class described consisting of a vanner belt, a horizontally disposed brush; a rod operated parallel to said brush, and contacting therewith; a padded roller below and parallel with said brush, perforated pipes to spray 15 the said brush, rod and roller; means to adjust the position of said brush, rod and roller laterally; and means to operate said brush and roller.
3. In an attachment for concentrators the 20 combination with a vanner belt, of a horizontally disposed brush contacting with the outer surface of said belt; a rod contacting with said brush; and a horizontally disposed and longitudinally reciprocated trough into 25 which the concentrates from said belt and brush are caught.
4. In an attachment for concentrators the 30 combination with a vanner belt; of a horizontally disposed brush contacting with the outer surface of said belt; a rod contacting with said brush; means to spray the surface of said brush, belt and rod at the points of contact.
- 35 5. In an attachment for concentrators the combination with a vanner belt; of a horizontally disposed brush contacting with the
- outer surface of said belt; a padded roller below said brush and contacting with the outer surface of said belt; and means to spray the surface of said belt, brush and 40 padded roller at the points of contact.
6. In an attachment for concentrators the combination with a vanner belt, of a horizontally disposed brush contacting with the outer surface of said belt; a padded roller 45 below said brush and contacting with the outer surface of said belt; and perforated pipes to spray the surface of said belt at the points of contact with said brush and belt.
7. In an attachment for concentrators the 50 combination with a vanner belt, of a horizontally disposed brush contacting with the outer surface of said belt; a padded roller below said brush and contacting with the outer surface of said belt; perforated pipes 55 to spray the surface of said belt at the points of contact with said brush and belt; means to adjust the position of said brush, roller and pipes relative to said vanner belt.
8. In an attachment for concentrators 60 the combination with a vanner belt, of a horizontally disposed padded roller the surface of which contacts with the surface of said vanner belt; an inclined trough having a portion extending upwardly and bent outwardly into contact with the padded roller, the contact edge of said portion being padded; and means to spray said padded roller at its point of contact with the padded trough-edge. 65

FRANCIS R. HARDIE.
